UNITED STATES PATENT OFFICE.

DRED P. HAYNES, OF ANNISTON, ALABAMA.

LOCK.

Application filed November 11, 1924. Serial No. 749,349.

To all whom it may concern:

Be it known that I, DRED P. HAYNES, a citizen of United States, residing at Anniston, Alabama, have invented certain new and useful Improvements in Locks, of which the following is a specification.

This invention relates to locks, and has special reference to a sliding bolt permutation lock.

10 One object of the invention is to provide an improved general construction of devices of this character.

A second important object of the invention is to provide an improved lock of this 15 class wherein a novel form of sliding bolt is employed.

A third important object of the invention is to provide a new and useful arrangement in such a lock for holding the bolt against 20 accidental movement.

With the above and other objects in view as will be hereinafter apparent, the invention consists in general of certain details of construction and combination of parts hereinafter more fully described, illustrated in the accompanying drawing and specifically claimed.

In the accompanying drawings, like characters of reference indicate like parts in the 30 several views, and:

Fig. 1 is a front view of the lock.

Fig. 2 is a back view thereof.

Fig. 3 is a section on the line 3-3 of Fig. 1.

35 Fig. 4 is a side elevation of one of the plungers or locking members.

Fig. 5 is an inside view of the back or combination plate.

Fig. 6 is a perspective view of one of the 40 keepers employed herewith.

Fig. 7 is a view of the bolt removed from the casing.

Fig. 8 is an inside view of the top or cover plate.

45 Fig. 9 is a top view of the intermediate plate or liner.

Fig. 10 is a view showing the manner in which the locking pins or plungers operate to hold the bolt against movement.

50 Fig. 11 is a view showing one application

of the device, the particular use being shown as that of a door bolt.

In the present form of the invention, there is shown a base plate 10, having a centrally disposed longitudinal groove 11, the base plate thus being of shallow channel form. This base plate is provided with rows of openings 12, each half of said openings being semi-circular, but one-half being of greater diameter than the other. In addition one of these openings, preferably an end opening in the center row, is provided with extension recess 13.

In this base plate is seated a liner 14 also having a longitudinal shallow groove 15, and this liner is provided with a set of circular openings 16 corresponding in number and position with the openings 12, the centers of the openings 16 being aligned with the centers on which the major and minor halves of the openings 12 are struck. Above the liner 15 is positioned a top plate 17 having openings 18 therein corresponding with the openings 16, and this top plate is provided with a pair of longitudinally extending grooves 19. With the top plate in position a slot is formed wherein slides a bolt 20. It is to be noted that the liner plate 15 has the openings 16 therein so arranged that one-half of these openings, in the outside row, lie in what may be termed the walls of the plate, while the remaining halves lie in the groove. This can be seen clearly by reference to Figure 10.

Now the bolt 20 has side notches 21 which correspond in number and spacing to the side openings 16 of the plate 15, and consequently to the side rows of openings 12. Also the bolt 20 has a series of slots 22, each terminating at one end in a circular opening 23, these slots and openings corresponding in number and position to the central rows of openings 12, 16, and 18. Seated in the grooves 19 are strips 24, which act as keeper means. The bolt is preferably provided at one end with an operating knob 25. When the various parts are assembled, it will be noted that the openings 12, 16 and 18 are aligned, and through each of these openings extends a pin 26 having a knurled turning 100

head 27, said head being provided with suitable indicia as shown in Fig. 1.

Each of these pins is held in position by the engagement of the spring or keeper 24 with a groove 24^a formed around the respective pin and each is cut half way through as at 28^a, on a level with the bolt 20. Furthermore, each pin has extending through its top, a slot wherein slides a locking pin 28^b, held in set position so that one end of the other projects outwardly by a screw 28. Now, with one end of the locking pin projecting outwardly the pins, when turned to bring that end against the upper shoulder of its opening 12, will allow movement of the bolt through the gap 28^a while, when turned to bring the pin in its opposite direction a locking effect will be produced. By setting the parts 28^b in proper position it will be seen that certain of the indicia will have to be turned upside down to permit movement of the bolt. Consequently, any one or more of these locking elements may be set so as to require certain of the pins 26 to be turned in one direction and the remainder in the other. For instance, referring to Fig. 10, it will be seen that when the pins are turned in one position, they allow free movement of the bolt while, in any other position, they lock the bolt. As for instance, the pins in that figure lettered 26^a lock the bolt, while the pins 26^b are in position to let the bolt move. These pins can be so adjusted by means presently to be described that any particular number of pins may be used for controlling the combination. That is to say, the indicia in any certain number of pins may be turned to known position to effect release of the bolt. For instance, all of the indexes, which are here shown as letters of the alphabet for convenience in distinguishing from the reference characters, may be required to be placed in upright position except, say, C, G and M, which may be arranged to be inverted to release the bolt. Now under these circumstances, unless this entire combination is effected, the bolt cannot move.

The device has many applications, as for instance, it may be used for a door bolt being mounted on a swinging door of the ordinary type, such as is indicated at 30, the door closing against the jamb 31, and the bolt being provided with a keeper 32 of ordinary construction.

Having thus described the invention, what is claimed as new is:

1. A base plate having a longitudinal channel extending therealong, a liner seated in said channel and having a similar longitudinal channel, a cover plate extending over said liner, said liner, base plate and cover plate being secured together to form a longitudinal slot, a locking bolt slidable in said slot, said base plate, liner and cover

plate being provided with aligned openings, said openings being arranged to lie with their centers on the edges of the longitudinal slot, the bolt having semi-circular recesses spaced to conform to said openings, cylindrical pins extending through said openings and cutaway diametrically opposite said bolt, heads on said pins having combination indicia thereon, and means to hold said pins in said openings. 75

2. A base plate having a longitudinal channel extending therealong, a liner seated in said channel and having a similar longitudinal channel, a cover plate extending over said liner, said liner, base plate and cover plate being secured together to form a longitudinal slot, a locking bolt slidable in said slot, said base plate, liner and cover plate being provided with aligned openings, said openings being arranged to lie with their centers on the edges of the longitudinal slot, the bolt having semi-circular recesses spaced to conform to said openings, cylindrical pins extending through said openings and cutaway diametrically opposite said bolt, heads on said pins having combination indicia thereon, means to hold said pins in said openings, other pins extending centrally through said base plate, liner, cover and bolt, the bolt being provided with slotted openings terminating in circular openings to accommodate the last mentioned pins. 85

3. A base plate having a longitudinal channel extending therealong, a liner seated in said channel and having a similar longitudinal channel, a cover plate extending over said liner, said liner, base plate and cover plate being secured together to form a longitudinal slot, a locking bolt slidable in said slot, said base plate, liner and cover plate being provided with aligned openings, said openings being arranged to lie with their centers on the edges of the longitudinal slot, the bolt having semi-circular recesses spaced to conform to said openings, cylindrical pins extending through said openings and cutaway diametrically opposite said bolt, heads on said pins having combination indicia thereon, means to hold said pins in said openings, said cover plate being provided with a pair of longitudinal grooves, and keepers located in said grooves and holding said pins. 100

4. A base plate having a longitudinal channel extending therealong, a liner seated in said channel and having a similar longitudinal channel, a cover plate extending over said liner, said liner, base plate and cover plate being secured together to form a longitudinal slot, a locking bolt slidable in said slot, said base plate, liner and cover plate being provided with aligned openings, said openings being arranged to lie with their centers on the edges of the longitudi- 115 120 125 130

nal slot, the bolt having semi-circular recesses spaced to conform to said openings, cylindrical pins extending through said openings and cutaway diametrically opposite said bolt, heads on said pins having combination indicia thereon, means to hold said pins in said openings, said cover plate being provided with a pair of longitudinal grooves, other pins extending centrally

through said base plate, liner, cover and bolt, the bolt being provided with slotted openings terminating in circular openings to accommodate the last mentioned pins, and keepers located in said grooves and securing said pins. 10
15

In testimony whereof I affix my signature.

DRED P. HAYNES.
